Primary Examiner—Lucy J. Lieberman*Attorney, Agent, or Firm*—Alexander J. McKillop; George W. Hager, Jr.; Michael J. Mlotkowski**[57] CLAIM**

The ornamental design of a bottle, as shown and described.

DESCRIPTION

FIG. 1 is a perspective view of a bottle, showing our new design;
 FIG. 2 is a top plan view thereof;
 FIG. 3 is a bottom plan view thereof;
 FIG. 4 is a front view thereof;
 FIG. 5 is a back view thereof; and,
 FIG. 6 is a side elevation, the opposite side elevation is a mirror image thereof except for the conventional screw threading on the bottle neck.

FIG. 1

FIG. 4

FIG. 2

FIG. 3

FIG. 6

FIG. 5
